US00D783096S

(12) **United States Design Patent** (10) Patent No.: **US D783,096 S**
 Aoki et al. (45) Date of Patent: ** Apr. 4, 2017

(54) **GAME DISPLAY SCREEN WITH MULTIPLE ARRAYS OF REELS**(71) Applicant: **WMS Gaming Inc.**, Waukegan, IL (US)(72) Inventors: **Dion K. Aoki**, Santa Monica, CA (US); **Shawn C. Collette**, Henderson, NV (US); **Allon G. Engman**, Chicago, IL (US)(73) Assignee: **Bally Gaming, Inc.**, Las Vegas, NV (US)(***) Term: **14 Years**(21) Appl. No.: **29/510,428**(22) Filed: **Nov. 27, 2014****Related U.S. Application Data**

(63) Continuation of application No. 29/507,253, filed on Oct. 24, 2014, now Pat. No. Des. 771,193, which is a continuation of application No. 14/101,400, filed on Dec. 10, 2013, now Pat. No. 9,251,670, which is a continuation of application No. 13/294,428, filed on Nov. 11, 2011, now Pat. No. 8,608,544.

(57) **CLAIM**

We claim the ornamental design for a game display screen with multiple arrays of reels, as shown and described.

DESCRIPTION

The FIGURE illustrates an image of a game screen displaying multiple arrays of reels.

The broken lines depict unclaimed environmental subject matter.
